TO OTTO R. BARNETT, OF CHICAGO, ILLINOIS.

RAIL-STAY.

1,228,613.

Specification of Letters Patent.

Patented June 5, 1917.

Application filed May 29, 1916. Serial No. 100,452.

To all whom it may concern:

Be it known that I, HIRAM H. SPONENBURG, a citizen of the United States, residing at Gurnee, in the county of Lake and State of Illinois, have invented certain new and useful Improvements in Rail-Stays, of which the following is a specification.

My invention relates to a rail stay, that is, to a device for preventing the longitudinal creep of railroad rails.

A rail stay consisting of a single unitary structure has advantages over a device consisting of two or more separate parts. Devices of the one-piece type are more conveniently handled by the track men. Where track devices of this character consist of more than one part there is always likelihood that in shipping and handling some of the parts will become lost or mislaid; or through inadvertence a larger or smaller quantity of one part may be supplied to a given station than of the other part or parts, which occasions inconvenience and waste. On the other hand, one piece rail stays or anti-creepers of the types used heretofore have ordinarily been deficient in one important respect. The hold which they take is not sufficiently firm and reliable. They are very likely to be shaken loose or otherwise disturbed from their operative position. For example, when the device consists of a rail engaging yoke or bar formed with a foot or flange adapted to bear against the cross tie, the movement of the device away from the tie, when the rail contracts with a fall of temperature, is likely to be interfered with by the ballast, particularly in winter time when the ballast is frozen. It frequently happens, under these circumstances, that the foot or tie abutting flange sticking in the ballast wrenches the device from the rail or loosens its grip thereon sufficiently to make the device inoperative. Besides this the constant vibration of the rail will soon affect the hold on the rail of a device which is rigid and depends only on friction for keeping it in place.

The principal object of my present invention is to provide a rail stay which comprises two separate parts united so that the device may be handled as a unitary struc-

ture but in such manner that the rail engaging member, which is formed so as to take a firm and reliable hold on the rail, may be capable of movement with the rail, 55 when the latter expands and contracts, for example, without reference to the member which bears against the tie so that the latter, if need be, may remain in position against the tie.

A further object is to provide a rail stay which can be economically manufactured and which will be light in weight and will have the necessary strength and holding power.

The invention consists in the construction and arrangements to be hereinafter described and claimed for carrying out the above stated objects and such other objects as will appear from the following description.

The invention is illustrated, in certain preferred embodiments, in the accompanying drawings, wherein—

Figure 1 is a side elevation of the device 75 as applied to the rail, with the rail shown in section.

Fig. 2 is a plan view of the rail stay and portions of the rail and tie.

Fig. 3 is a sectional view on line 3—3 of 80 Fig. 1.

Figs. 4 and 5 are views, in perspective, of the two parts of the rail stay.

Fig. 6 is a fragmentary view of a rail stay, illustrating a modified construction 85 of the foot member, and

Fig. 7 is a perspective view of the modified foot member.

Like characters of reference designate like parts in the several figures of the drawings.

Referring first to Figs. 1 to 5 inclusive, A designates the railroad rail and B one of the cross ties on which the rail is held. The rail stay shown in these figures consists of a rail engaging member 10 and a foot or tie 95 abutting member 11.

The rail engaging member 10 is composed, preferably, of a flat bar of steel having a certain amount of resiliency, one end of which is bent over, as indicated at 12, to 100 engage and overlap one edge of the base flange of rail A. The other end of the bar

is given a quarter twist, as shown at 13, so that the extremity of the bar stands edge-wise with respect to the base of the rail. This end of the bar is curved around so as 5 to form a spring rail engaging member 14 notched at its end at 15 to engage the edge of the base flange of the rail.

The foot member 11 is formed with a horizontal plate 16, the width of which is 10 reduced at its outer end to provide shoulders 17. The narrowed portion of the tongue lies in a depressed seat 18 with which the bar 20 is formed. The tongue is secured to the bar by means of a soft metal rivet 15 19 which is small and light enough so that the forces exerted by the movement of the rail will shear it without difficulty. The two members of the device are fastened together preferably so that a slight 20 space 20 (Fig. 2) intervenes between the bar and the shoulders 17. The first creeping movement of rail A will shear the rivet, whereupon further creeping movement is checked by the bar 10 coming in 25 contact with the shoulders 17 on the tie abutting member.

In applying the rail engaging member 10 to the rail the spring member 14 has to be 30 expanded so that the rail engaging member has a resilient engagement with the rail which absorbs vibration and prevents looseness from this or any other cause. The lip 35 21 above the notch 15 stands oblique to the length of the rail so that any tendency of the rail to creep forces the point 22 of the lip higher up on the slope of the base flange, producing a tighter bind of the device on the rail at this place. The extremity of the lip, however, stands more nearly in line with 40 the length of the rail than transversely thereof so that the lip, though relatively small, has very considerable strength as against the forces exerted upon it.

The rivet 19 holds the parts of the device 45 together so that the device can be handled as a unitary structure, thus doing away with the inconvenience and waste which usually attends the use of rail stays made up of a plurality of parts. For purposes of transportation and application to the rail the device is a one-piece rail stay. As soon, however, as the rivet is sheared the rail engaging member is structurally separate from the tie abutting member so that when the rail 55 contracts, as it necessarily will with a fall of temperature, the rail engaging member will move freely away from the tie without disturbing the position of the foot, which may be frozen into the ballast, or for other reasons may be prevented from moving with the 60 movements of the rail.

Obviously the same objects might be attained by different means. One different expedient is illustrated in Fig. 6. The foot 65 member, in this case, is a malleable casting

consisting of a tie abutting flange 23 and a bifurcated tongue between the members 24 and 25 of which the bar or tie engaging member 10^a extends. The lower member 25 of the tongue may be bent up, as indicated at 70 26, after the tie engaging member has been put in place to hold the parts in engagement. The rail engaging member still has some freedom of movement with respect to the foot member. If this is not enough to 75 allow for the full contraction of the rail the bent up portion 26 is readily pressed back into its original shape by the rail engaging member when the latter moves backwardly from the tie. 80

While I have described my invention in certain preferred embodiments, it will be understood that further modifications might be made without departure from the principles of the invention. Therefore I do not wish 85 to be understood as limiting the invention to the precise constructions, arrangements and devices shown except so far as certain of the claims herein may be specifically so limited. 90

I claim:

1. A rail stay comprising a member adapted to engage a rail and a foot member adapted to bear against the tie; said members being engaged one with the other for handling 95 as a unitary device but so that the rail engaging member may move, relatively to the foot member, with the longitudinal movements of the rail when engaged therewith.

2. A rail stay comprising a member adapted to engage a rail and a foot member adapted to bear against a tie; said members being engaged one to the other for handling as a unitary device but so that the rail engaging member may, when engaged with the rail, 105 have free, unimpeded movement to and from the part of the foot member bearing against the tie.

3. A rail stay comprising a resilient member adapted to engage a rail by spring action, 110 and a foot member adapted to bear against the tie; said members being engaged one with the other for handling as a unitary device but so that the rail engaging member may move, relatively to the foot member, 115 with the longitudinal movements of the rail when engaged therewith.

4. In a rail stay, the combination of a rail engaging member consisting of a flat bar of metal to extend under the base of a rail and provided at opposite ends with means for engaging opposite edges of the rail base, and a foot member adapted to bear against a tie and formed with a tongue to extend between the rail engaging member and the rail; said 125 tongue and rail engaging member being engaged one to the other to permit the device to be handled as a unitary structure but so that the rail engaging member may move, relatively to the foot member, with the longi- 130

tudinal movements of the rail when engaged therewith.

5. In a rail stay, the combination of a rail engaging member consisting of a flat bar of 5 spring metal to extend under the base of a rail and provided at opposite ends with means for resiliently engaging opposite edges of the rail base, and a foot member adapted to bear against a tie and formed 10 with a tongue to extend between the rail engaging member and the rail; said tongue and rail engaging member being engaged one to the other to permit the device to be handled as a unitary structure but so that the rail 15 engaging member may move, relatively to the foot member, with the longitudinal movements of the rail when engaged therewith.

6. In a rail stay, the combination of a rail 20 engaging member consisting of a flat bar of metal to extend under the base of a rail, formed at one end with rail engaging means, the other end being bent into vertical position and formed with a notch in its extremity 25 to engage an edge of the rail base, and a foot member adapted to bear against a tie and formed with a tongue to extend between the rail engaging member and the rail; said tongue and rail engaging member being engaged 30 one to the other to permit the device to be handled as a unitary structure but so that the rail engaging member may move, relatively to the foot member, with the longitudinal movements of the rail when engaged 35 therewith.

7. In a rail stay, the combination of a rail engaging member consisting of a flat bar of 40 spring metal to extend under the base of a rail, formed at one end with rail engaging means, the other end being bent into vertical position to form a spring hook adapted to resiliently engage an edge of the rail base, and a foot member adapted to bear against 45 a tie and formed with a tongue to extend between the rail engaging member and the rail; said tongue and rail engaging member being engaged one to the other to permit the device to be handled as a unitary structure but so that the rail engaging member 50 may move, relatively to the foot member, with the longitudinal movements of the rail when engaged.

8. In a rail stay, the combination of a rail engaging member composed of a flat 55 bar of spring metal to extend under the base of a rail, bent over at one end to overlap one edge of said rail base, the other end of said bar being notched at its extremity and bent so as to provide a resilient hook 60 standing edgewise of the rail base and engaging the edge thereof, and a foot member adapted to bear against a tie and formed with a tongue to extend between the rail engaging member and the rail; said tongue 65 and rail engaging member being engaged

one to the other to permit the device to be handled as a unitary structure but so that the rail engaging member may move, relatively to the foot member, with the longitudinal movements of the rail when engaged 70 therewith.

9. In a rail stay, the combination of a rail engaging member consisting of a flat bar of metal to extend under the base of a rail and provided at opposite ends with 75 means for engaging opposite edges of the rail base, a foot member adapted to bear against a tie and formed with a tongue to extend between the rail engaging member and the rail, and a device for engaging the tongue and bar which is of a character to be severed by the movement of the rail engaging member with the rail.

10. In a rail stay, the combination of a rail engaging member consisting of a flat 85 bar of metal to extend under the base of a rail and provided at opposite ends with means for engaging opposite edges of the rail base, a foot member adapted to bear against a tie and formed with a tongue to 90 extend between the rail engaging member and the rail, and a rivet uniting said tongue and bar of a character to be sheared by the movement of the rail engaging member with the rail.

11. A rail stay comprising a member adapted to engage a rail, a foot member adapted to bear against a tie, and a device for securing said members together of a character to be severed by the movement of 100 the rail engaging member with the rail.

12. A rail stay comprising a member adapted to engage a rail, a foot member adapted to bear against a tie, and a rivet for securing said members together of a character to be severed by the movement of the rail 105 engaging member with the rail.

13. A rail stay comprising a member adapted to engage a rail; a member adapted to engage a tie, and severable means for connecting said members together in operative position with respect to each other.

14. A rail stay comprising a rail engaging member adapted to engage a rail with 115 spring action, a tie engaging member, and severable means for connecting said members together in operative position with respect to each other.

15. A rail stay comprising a rail engaging member, a tie abutting member provided with an abutment for the rail engaging member, and severable means for connecting the rail engaging member to the tie engaging member at a point a short distance from 120 said abutment.

16. In a rail stay, the combination of a rail engaging member consisting of a flat bar of steel, one end of which is bent over to overlap one edge of the base of a rail, the other end of which is notched and bent so 125 130

as to form a hook standing edgewise with respect to the rail base and adapted to resiliently engage the same, an intermediate portion of the bar being formed with a seat, a tie abutting member consisting of a tie abutting flange and a horizontal plate reduced in width at the end to provide a tongue

which lies in said seat between the bar and the rail base, shoulders against which the bar is adapted to bear, and a rivet for securing the bar to the tongue at a point which initially holds said bar spaced away from said shoulders.

HIRAM H. SPONENBURG.

Corrections in Letters Patent No. 1,228,613.

It is hereby certified that in Letters Patent No. 1,228,613, granted June 5, 1917, upon the application of Hiram H. Sponenburg, of Gurnee, Illinois, for an improvement in "Rail-Stays," errors appear in the printed specification requiring correction as follows: Page 1, line 93, for the word "held" read *laid*; page 2, line 13, for the reference-numeral "20" read 10; and that the said Letters Patent should be read with these corrections therein that the same may conform to the record of the case in the Patent Office.

Signed and sealed this 14th day of August, A. D., 1917.

[SEAL.]

R. F. WHITEHEAD,

Acting Commissioner of Patents.
